UNITED STATES PATENT OFFICE.

CHARLES F. HANINGTON, OF ROSELLE PARK, NEW JERSEY.

TRANSOM-OPERATING MECHANISM.

No. 895,013.

Specification of Letters Patent.

Patented Aug. 4, 1908.

Application filed July 13, 1907. Serial No. 383,665.

To all whom it may concern:

Be it known that I, CHARLES F. HANINGTON, a citizen of the United States, and a resident of Roselle Park, county of Union, and State of New Jersey, have invented certain new and useful Improvements in Transom-Operating Mechanism, of which the following is a specification.

My invention relates to mechanism for operating transoms and the like.

The object of my invention is to provide an improved transom operating device which will facilitate the operation of the transom, that is—opening, closing and locking the transom in any of its positions.

A further object is to provide a construction by which the greater portion of the mechanism may be concealed within the door frame.

20 The invention comprises more specifically speaking a lever fulcrumed at an intermediate point having one of its arms connected through suitable devices with the transom and its other arm suitably connected with a lever 25 operating and locking means. I prefer to employ a rock shaft suitably journaled in the door frame having a spring arm fixed thereon suitably connected with the transom, and also having fixed to it a rock shaft which is 30 slotted to receive a pin provided on one arm of the fulcrumed lever, the other arm of the fulcrumed lever being engaged by the lever operating and locking means, which latter is adapted to be actuated by hand.

35 An embodiment of my invention with several modifications of certain parts is shown in the accompanying drawings, of which.

Figure 1 is a side elevation showing the door frame, a transom and operating device 40 with the preferred form of lever operating means; Fig. 2 is a detail elevation, part in section, showing the rock shaft, rock arm and spring arm hereafter referred to; Fig. 3 is a detail sectional elevation of the lever operating 45 means shown in Fig. 1; Fig. 4 is a detail elevation of a modified form of lever operating and locking means; Fig. 5 is a detail view showing a part of the lever operating means shown in Fig. 4, with special reference 50 to the locking and unlocking operation; and Fig. 6 is a detail elevation of a further modified form of lever operating and locking means.

Referring now more specifically to said drawings, 10 indicates the door frame in which is suitably mounted the transom 11. The transom 11 may be mounted in the

frame by hinges as shown at 12. Journaled in the door frame 10 is a rock shaft 13 which has a square end as shown at 14, upon which is mounted a sleeve 15 which may be keyed thereto by a set screw 16 and which has a spring arm 17 suitably bent as shown clearly in Fig. 1, and passing loosely under a retainer 18 on the transom 11 to permit a slight sliding movement.

65 The outer end of rock shaft 13 has suitably fixed thereon the rock arm 19 which has a slot and pin connection as by slot 20 and pin 21 with one arm of a lever 22 fulcrumed at intermediate point 23 in the door frame. It is obvious that although I have here shown the slot 20 as being in the rock arm 19 and the pin 21 as being on one arm of fulcrumed lever 22, the pin 21 could just as well be on rock arm 19 and the slot 20 be formed in fulcrumed lever 22. The slot 20 is diagonally disposed in the rock arm 19 to provide a certain acceleration of movement which is thereby obtained upon rocking the rock arm 19 into a position shown in dotted lines in Fig. 1 70 by operating the fulcrumed lever 22. The lower arm of the fulcrumed lever 22 is slotted as shown at 24 in Fig. 1 to receive a pin 25 mounted on an extension 26 of a threaded nut 27 which is moved by rotation of the worm 28 passing through it. The rotation of the worm 28 is designed to be affected by an actuating handle 29. The rotation of the worm 28 moves the nut 27 which by means of the pin 25, thus operates the fulcrumed 75 lever 22 by which the transom is closed and opened. The pitch of the thread on the worm 28 provides for the locking of the fulcrumed lever 22. The worm 28 is suitably journaled in a housing or frame 30, the upper portion of which 31 serves as a guide or retainer for the extension 26 of nut 27 as clearly shown in Fig. 3.

80 Other means may be employed to effect the operating and locking of the fulcrumed lever 22. For example, in Fig. 4, I have shown a segment gear 32 pivoted at 33 which is provided with a slot 34 engaging the pin 35 on the lower arm of the fulcrumed lever 22. Rotation of the segment gear 32 on the pivot 85 33, thus obviously operates the fulcrumed lever 22. For the purpose of rotating said segment gear 32 a pinion 36 is provided which is mounted upon the rod 37 which is suitably journaled and passing through the 90 face of the door frame, has fixed on its outer end a hand actuating lever 38. The pinion

36 meshes with the teeth of segment gear 32 and in rotating the rod 37 by turning the handle 38, the movement is transmitted to the segment gear 32. The rod 37 has sufficient reciprocating movement in its journals to permit me to provide a locking pin 39 which is adapted to engage and hold the pinion 36 when the latter is in a normal position in which it is held by means of a spring 40. 5 To unlock the pinion 36 the handle 38 is drawn outward and thus the pinion 36 moved against the tension of spring 40 out of engagement with the locking pin 39, the return to locking position being automatic by 10 the action of spring 40. In this form of lever operating and locking means a guide frame 41 is provided whose flange 42 serves to guide and hold in place the segment gear 32 and whose flanges 43 and 44 may serve as 15 journal bearings for the rod 37.

A still further modified form of lever operating and locking means is illustrated in Fig. 6. In this form an actuating handle 45 may operate a lever 46 suitably guided in a frame 25 47 and provided with a slot 48 engaging the pin 35 in fulcrumed lever 22. The lever 46 passes through a guide plate 49 on the door frame and has on its under portion slots 50 which are normally moved into engagement 30 with the bottom of guide 49 by a spring 51 as clearly shown in Fig. 6. To operate the lever, the handle 45 is raised, thus moving the lever 46 against the tension of spring 51 out of its locking engagement with the bottom of 35 guide 49, and the lever may then be reciprocated to operate the fulcrumed lever 22.

What I claim is:

1. In a transom operating device, the combination with the transom suitably mounted 40 in the upper portion of the door frame, an elongated lever substantially vertically disposed within the door frame and fulcrumed at an intermediate point therein, and a transom operating connection between the upper portion of said fulcrumed lever and said transom; of a lever operating means operatively connected with the lower portion of 45 said fulcrumed lever.

2. In a transom operating device, the combination with the transom suitably mounted 50 in the upper portion of the door frame, an elongated lever substantially vertically disposed within the door frame and fulcrumed at an intermediate point therein and a transom operating connection between the upper portion of said fulcrumed lever and said transom; of a lever operating and locking means operatively connected with the lower portion of 55 said fulcrumed lever.

60 3. In a transom operating device, the combination with the transom, suitably mounted in the upper portion of the door frame, an elongated lever substantially vertically disposed in the door frame and fulcrumed at an intermediate point therein, a rock arm suit-

ably journaled in the door frame and operatively connected with said transom and with the upper portion of said fulcrumed lever; of a lever operating means operatively connected with the lower portion of said fulcrumed lever. 75

4. In a transom operating device, the combination with the transom suitably mounted in the upper portion of the door frame, an elongated lever substantially vertically disposed within the door frame and fulcrumed at an intermediate point therein, a rock arm suitably journaled in the door frame and operatively connected with said transom and with the upper portion of said fulcrumed lever; of a lever operating and locking means operatively connected with the lower portion of 80 said fulcrumed lever.

5. In a transom operating device, the combination with the transom suitably mounted in the upper portion of the door frame, an elongated lever substantially vertically disposed within the door frame and fulcrumed at an intermediate point therein and a suitably mounted rock arm operatively connected with said transom and having a slot and pin connection with the upper portion of 85 said fulcrumed lever; of a lever operating means operatively connected with the lower portion of said fulcrumed lever. 90

6. In a transom operating device, the combination with the transom suitably mounted in the upper portion of the door frame, an elongated lever substantially vertically disposed within the door frame and fulcrumed at an intermediate point therein and a suitably mounted rock arm operatively connected with said transom and having a slot and pin connection with the upper portion of 95 said fulcrumed lever; of a lever operating and locking means operatively connected with the lower portion of said fulcrumed lever. 100

7. In a transom operating device, the combination with the transom suitably mounted in the upper portion of the door frame, an elongated lever substantially vertically disposed in said door frame and fulcrumed at an intermediate point therein and a suitably mounted rock arm operatively connected with said transom and having a diagonal-slot and pin connection with the upper portion of 110 said fulcrumed lever; of a lever operating means operatively connected with the lower portion of said fulcrumed lever. 115

8. In a transom operating device, the combination with the transom suitably mounted in the upper portion of the door frame, an elongated lever substantially vertically disposed within the door frame and fulcrumed at an intermediate point therein, and a suitably mounted rock arm operatively connected with said transom and having a diagonal-slot and pin connection with the upper portion of 120 said fulcrumed lever; of a lever operating and locking means operatively connected with the lower portion of said fulcrumed lever. 125

nected with the lower portion of said fulcrumed lever.

9. In a transom operating device, the combination of the transom hinged below in the upper portion of the door frame, a rock shaft suitably journaled in the door frame, an arm fixed on said rock shaft and connected with the upper portion of said transom, a rock arm fixed on said rock shaft, an elongated lever substantially vertically disposed in the door frame and fulcrumed at an intermediate point therein, an operating connection between said rock arm and the upper portion of said fulcrumed lever, and a lever operating means operatively connected with the lower portion of said fulcrumed lever.

10. In a transom operating device, the combination of the transom hinged below in the upper portion of the door frame, a rock shaft suitably journaled in the door frame, an arm fixed on said rock shaft and suitably connected with the upper portion of the transom, a rock arm fixed on said rock shaft, an elongated lever substantially vertically disposed within the door frame and fulcrumed at an intermediate point therein, an operating connection between said rock arm and the upper portion of said fulcrumed lever and a lever operating and locking means operatively connected with the lower portion of said fulcrumed lever.

11. In a transom operating device, the combination of the transom hinged below in the upper portion of the door frame, a rock shaft journaled in the door frame, an arm fixed on said rock shaft and connected with the upper portion of said transom, a rock arm fixed on said rock shaft, an elongated lever substantially vertically disposed within the door frame and fulcrumed at an intermediate point therein, a slot and pin connection between said rock arm and the upper portion of said fulcrumed lever and a lever operating means operatively connected with a portion of said fulcrumed lever.

12. In a transom operating device, the combination of the transom hinged below in the upper portion of the door frame, a rock shaft journaled in the door frame, an arm fixed on said rock shaft and suitably connected with the upper portion of said transom, a rock arm fixed on said rock shaft, an elongated lever substantially vertically disposed within said door frame and fulcrumed at an intermediate point therein, a slot and pin connection between said rock arm and the upper portion of said fulcrumed lever and a lever operating and locking means operatively connected with the lower portion of said fulcrumed lever.

13. In a transom operating device, the combination of the transom hinged below in the upper portion of the door frame, a rock shaft suitably journaled in the door frame, an arm fixed on said rock shaft and suitably

connected with the upper portion of said transom, a rock arm fixed on said rock shaft, an elongated lever substantially vertically disposed within the door frame and fulcrumed at an intermediate point therein, a diagonal-slot and pin connection between said rock arm and the upper portion of said fulcrumed lever and a lever operating means operatively connected with the lower portion of said fulcrumed lever.

14. In a transom operating device, the combination of the transom suitably hinged below in the upper portion of the door frame, a rock shaft suitably journaled in the door frame, an arm fixed on said rock shaft and suitably connected with the upper portion of said transom, a rock arm fixed on said rock shaft, an elongated lever substantially vertically disposed within the door frame, and fulcrumed at an intermediate point therein, a diagonal-slot and pin connection between said rock arm and the upper portion of said fulcrumed lever, and a lever operating and locking means operatively connected with the lower portion of said fulcrumed lever.

15. In a transom operating device, the combination with the transom suitably mounted in the door frame, an elongated lever substantially vertically disposed within the door frame and fulcrumed at an intermediate point therein, and a transom operating connection between the upper portion of said fulcrumed lever and said transom; of a suitably guided nut having suitable connection with the lower portion of said fulcrumed lever and a hand actuated worm in engagement with said nut.

16. In a transom operating device, the combination with the transom suitably mounted in the upper portion of the door frame, an elongated lever substantially vertically disposed within the door frame and fulcrumed at an intermediate point therein, and a suitably mounted rock arm operatively connected with said transom and with the upper portion of said fulcrumed lever; of a suitably guided nut having suitable connection with the lower portion of said fulcrumed lever and a hand actuated worm in operative engagement with said nut.

17. In a transom operating device, the combination with the transom suitably mounted in the upper portion of the door frame, an elongated lever substantially vertically disposed within the door frame and fulcrumed at an intermediate point therein and a suitably mounted rock arm operatively connected with said transom and having a slot and pin connection with the upper portion of said fulcrumed lever; of a suitably guided nut having operative connection with the lower portion of said fulcrumed lever and a hand actuated worm in operative engagement with said nut.

18. In a transom operating device, the

combination with the transom suitably inounted in the upper portion of the door frame, an elongated lever substantially vertically disposed within the door frame and 5 fulcrumed at an intermediate point therein and a suitably mounted rock arm operatively connected with said transom and having a diagonal-slot and pin connection with the upper portion of said fulcrumed lever; of a 10 suitably guided nut operatively connected with the lower portion of said fulcrumed lever and a hand actuated worm in operative connection with said nut.

19. In a transom operating device, the 15 combination of the transom suitably mounted in the upper portion of the door frame, a rock shaft suitably journaled in the door frame, an arm fixed on said rock shaft, and suitably connected with said transom, a rock 20 arm fixed on said rock shaft, an elongated lever substantially vertically disposed within the door frame and fulcrumed at an intermediate point therein, a diagonal-slot and pin connection between said rock arm and the 25 upper portion of said fulcrumed lever, a suitably guided nut operatively connected with the lower portion of said fulcrumed lever and a hand actuated worm in operative connection with said nut.

30 20. In a transom operating device, the combination with the transom suitably mounted in the upper portion of the door

frame, an elongated lever substantially vertically disposed within the door frame and fulcrumed at an intermediate point therein, 35 and a suitably mounted rock arm operatively connected with said transom and having a diagonal-slot and pin connection with the upper portion of said fulcrumed lever; of a suitably guided nut having a pin engaging a 40 slot in the lower portion of said fulcrumed lever, and a hand actuated worm in operative connection with said nut.

21. In a transom operating device, the combination of the transom hinged below in 45 the upper portion of the door frame, a rock shaft suitably journaled in the door frame, an arm fixed on said rock shaft and suitably connected with the upper portion of said transom, a rock arm fixed on said rock 50 shaft, an elongated lever substantially vertically disposed within the door frame and fulcrumed at an intermediate point therein, a diagonal-slot and pin connection between 55 said rock arm and the upper portion of said fulcrumed lever, a suitably guided nut having a pin engaging a slot in the lower portion of said fulcrumed lever and a hand actuated worm in operative engagement with said nut.

CHARLES F. HANINGTON.
